UNITED STATES PATENT OFFICE.

ELWIN W. DAVIS, OF GENEVA, MINNESOTA.

CAR-COUPING.

SPECIFICATION forming part of Letters Patent No. 320,337, dated June 16, 1885.

Application filed April 11, 1885. (No model.)

To all whom it may concern:

Be it known that I, ELWIN W. DAVIS, a citizen of the United States, and a resident of Geneva, in the county of Freeborn and State of Minnesota, have invented certain new and useful Improvements in Car-Couplings; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved car-coupling. Fig. 2 is a longitudinal vertical section of the same; and Fig. 3 is a horizontal section on line *xx*, Fig. 2.

Similar letters of reference indicate corresponding parts in all the figures.

My invention has relation to that class of car-couplings in which a common link is engaged within the draw-head by a spring-actuated hook; and it consists in the improved construction and combination of parts of the same, as hereinafter more fully described and claimed.

In the accompanying drawings, the letter A indicates the draw-head, which is formed with the usual recess, B, for the reception of the link, and the bottom of this recess has a longitudinal slot, C, extending from near the forward end of the same, while the top of the recess has a short slot, D, through which passes a bar, E, projecting upward from a bar, F, pivoted at its inner end in the inner end of the longitudinal slot C, and having its outer end formed into an upwardly-projecting hook, G. The under side of the hooked bar is provided with a downwardly-projecting lug, H, to which one end of a spiral spring, I, is secured, while the lower end of the said spring is secured to an upwardly-projecting lug, J, upon a downwardly-projecting oblique bar, K, secured at its upper end to the bottom of the draw-head, and extending with its free end under the pivoted hooked bar, the spring serving to force the hooked bar up into the longitudinal slot in the bottom of the draw-head. The recess in the draw-head has a transverse piece, L, against which the link may abut when inserted into the recess, and two curved

side pieces, M M, are secured at their inner ends to this cross-piece, and at their outer ends to the sides of the mouth of the recess of the draw-head, forming curved guides for the link. A flat spring, O, is secured at its inner end to the upper side of the cross-piece, and has its outer end curved upward, so as to bear against the roof of the recess, and this outer end of the spring is slotted or bifurcated, so as to fit over the upper end of the hook upon the forward end of the pivoted bar.

P is the link, which is of the usual construction, and it will be seen that when the link is introduced into the mouth of the recess in the draw-head the curved side guides will guide the link straight, while the curved spring-guide will guide the link and force it over the hook, whereupon its bifurcated end will engage the end of the hook and prevent the link from slipping over the end of said hook.

For the purpose of depressing the hooked bar, when it is desired to uncouple the link, the upwardly-projecting bar E has a transverse vertical slot, Q, into which one arm of an elbow-lever, R, projects, which lever is pivoted upon the top of the draw-head, and by forcing the upwardly-projecting arm S of this elbow-lever toward the upright bar the said bar and the hooked bar may be depressed, which will allow the link to be withdrawn from the draw-head.

Having thus described my invention, I claim and desire to secure by Letters Patent of the United States—

1. In a car-coupling, the combination of a hooked pivoted bar having a spring for forcing it upward and pivoted in the bottom of the recess in the draw-head, a flat spring secured at its inner end in the inner end of the recess of the draw-head, and having its outer end curved upward and bifurcated to fit with its bulged forward end over the hook of the bar, the link, and means for depressing the hooked bar, as and for the purpose shown and set forth.

2. In a draw-head having a spring-cushioned hook in its bottom, two curved side guides, M M, in combination with the flat spring O, having its outer end bifurcated and fitting over the end of the hook, as and for the purpose shown and set forth.

3. In a car-coupling, the combination of the draw-head having the recess B, slot C in its bottom, and slot D in its top, bar F, pivoted in slot C, and having spring I, forcing it upward, and formed with hook G at its outer end, cross-piece L, curved side guides, M M, flat spring O, having its outer end bifurcated, the link, and the upright bar E and elbow-lever R, for depressing the hooked bar, as and for the purpose shown and set forth.

In testimony that I claim the foregoing as my own I have hereunto affixed my signature in presence of two witnesses.

ELWIN W. DAVIS.
